DISPLAY RACK

David J. Maxin, Philadelphia, Pa., assignor to
Smith, Kline & French, Inc., Philadelphia, Pa.,
a corporation of Pennsylvania

Application December 27, 1935, Serial No. 56,332

1 Claim. (Cl. 211—85)

This invention relates to racks useful more particularly in retail stores for the stacking and display of boxed merchandise and the like.

My invention is directed toward the provision of a compact and attractive rack suitable for the purpose mentioned which is light in weight, yet sturdy; which is capable of economic manufacture from wire or bar metal of relatively small gauge; which affords a multiplicity of sections or compartments for the stacking of boxed merchandise of different kinds or brands with trademarks or other identifying symbols on them plainly visible, as well as holders for markers indicating the prices of the merchandise in the different sections; and which can be collapsed flat for convenience of storage and shipment.

Other objects and attendant advantages will appear from the detailed description which follows of the attached drawings, wherein Fig. I is a perspective view showing the manner in which my improved rack is intended to be used.

Fig. II is a perspective view of the rack by itself.

Fig. III is a plan sectional view taken as indicated by the arrows III—III in Fig. II.

Fig. IV shows the rack collapsed; and

Fig. V is a sectional view taken as indicated by the arrows V—V in Fig. IV.

From these illustrations, it will be noted that my improved rack is constructed wholly of wire or metallic rod stock of relatively small gauge and that it comprises a back component 1; a front component 2; end components 3, 4; and a pair of intermediate upright partition components 5, 6. As shown, these partition components 5, 6 set apart three columnar storage spaces 7, 8, 9 for stacked boxes B, B¹, and B² (Fig. I) containing merchandise of different makes or brands with trade-marks or other identifying symbols on them plainly visible from the front of the rack. The back component 1 of the rack is of stepped configuration, and embodies a central invert U-shaped member 10; two oppositely disposed counterpart flanking invert L-shaped members 11, 12 which are of a lesser height and have their top horizontals welded fast to the uprights of the central member at 13, 13; and a connecting horizontal member 15 near the bottom of the rack which is in turn welded fast at 16, 16 and 17, 18 to the uprights of both said central and flanking members. The lower ends of the verticals of the flanking members 11, 12 of the back component 1 are turned up to form rear supporting feet 19 and 20 for the rack and have their ends welded fast to the horizontal

member 15 at 21 and 22. At an intermediate level, the verticals of the central member 10 of the back component 1 are joined by a relatively short horizontal 23 which is welded fast at 24, 24. Permanently secured by welding centrally of 5 the tops of the three members 10, 11 and 12 of the back component 2 are upright holder clips 25, 26, and 27 for cards giving the price and/or other information regarding the merchandise in the three columns 7, 8, and 9. 10

The front component 2 of the rack includes end uprights 28, 29 and intermediate uprights 30, 31 which severally are connected in the horizontal plane of the bottom cross member 15 of the back component 1 by a horizontal 32 which is welded 15 fast to said uprights at 33, 34 and 35, 36, the latter having their lower portions turned up to form front feet 37, 38 for the rack with the ends welded fast to said horizontal 32 at 39, 40. In the plane of the intermediate horizontal 23 of the back component 1, the verticals 28—31 of the front component 2 are joined by a horizontal 41 which is welded fast to said verticals at 42, 43 and 44, 45. 20

The end components 3 and 4 are identical and of a height corresponding substantially to that of the flanking portions 11, 12 of the back component 1. As shown, the end components 3, 4 comprise top and bottom horizontals 46, 47 and 48, 49 respectively at the levels of the top horizontals of the flanking portions 11 and 12 of the back component 1 and the lower horizontals 15 and 32 respectively of the back and front components 1 and 2. As shown, the horizontals 46, 47, and 48, 49 of the end components 3 and 4 are connected by pairs of centrally-disposed 30 spaced verticals 50, 50 and 51, 51 and have their ends curled about the verticals of the flanking members 11, 12 of the back component 1 and the end verticals 28, 29 of the front component 2 as indicated respectively at 52, 53 and 54, 55. 35 At the level of the intermediate horizontal 41 of the front component 2, the end components 3 and 4 are provided with horizontals 56, 57 which have their ends freely curled about the verticals 45 of the flanking members 11, 12 of the back component 1 and the end verticals 28, 29 of the front component 2 as indicated at 58 and 59. The verticals 50 and 51 of the end members 3, 4 are welded fast to the horizontals 46, 47, 56 and 48, 49, 57 at 60 and 61 respectively. 40

The intermediate vertical partitions 5 and 6 are similar to the end components 3 and 4 but of a height corresponding substantially to that of the central member 10 of the back component 55

1. As shown, the vertical partitions 5 and 6 have upper and lower and intermediate horizontals 62, 63, 64 and 65, 66, 67 respectively with their ends freely curled about the verticals of the central 5 member 10 of the back component 1 and the intermediate verticals 30 and 31 of the front component 2 at 68, 69, 70 and 71, 72, 73 and which are joined by pairs of centrally disposed spaced verticals 75, 76 welded fast at 77, 78, 79 and 80, 10 81 and 82 respectively.

In order to support the stacks of boxes B, B¹ and B² the rack is provided with three bottom shelves 84, 85 and 86 also formed of wire with 15 curls 87, 88 and 89 freely embracing the lower horizontal 15 of the back component 1, and arranged with their front edges supported by the bottom horizontal 32 of the front component 2. I may also provide an additional shelf 90 of wire for the central compartment 7 of the rack with 20 its rear end hinged at 91 to the intermediate horizontal 23 of the back component 1 and its front edge resting on the intermediate horizontal 41 of the front component 2. The shelf 90 thus serves as an intermediate horizontal partition 25 for the central section with formation of upper and lower divisions which may be utilized as shown in Fig. I for boxes of different sizes containing the same brand of merchandise. In addition to supporting the price cards C, C¹ and C², 30 the holder clips function as back rests for boxes B, B¹ and B² placed upright for better display at the tops of the piles.

From the foregoing it will be seen that my invention affords a compact and attractive display 35 rack of inexpensive construction, which is light,

and, by virtue of having the parts of its several components welded together, is sturdy and strong. Due to the open design of the rack, it is readily accessible both from the front and the back for insertion of the boxes B, B¹ and B² initially, as well as withdrawal as the merchandise is sold. For convenience of storage and/or shipment, the rack may be collapsed flat, by swinging the hinged shelves up into the plane of the back component and then swinging the end and partition components in one direction or the other as permitted by the several pivotal connections until they lie flat, with the front component 2 against said back component as shown in Figs. IV and V.

15

Having thus described my invention, I claim:

A collapsible multi-column display rack comprising a back component with vertical end bars, vertical intermediate bars and connecting cross bars at different levels; a front component with 20 vertical end and intermediate cross bars corresponding to those of the back component; end components and intervening partitioning components having spaced vertical bars, and connecting cross bars at different levels having pivot 25 ears at opposite ends engaging the corresponding end and intermediate vertical bars of the back and the front components, and shelves in the several columns of the rack, each shelf being pivotally connected to a cross bar of the back component and adapted to rest with its swinging edge resting on a corresponding bar of the front component.
